UNITED STATES PATENT OFFICE.

JOHN A. PRICE, OF SCRANTON, PENNSYLVANIA.

WATER-HEATER FOR STOVES, RANGES, &c.

SPECIFICATION forming part of Letters Patent No. 308,927, dated December 9, 1884.

Application filed March 17, 1884. (No model.)

To all whom it may concern:

Be it known that I, JOHN A. PRICE, of Scranton, in the county of Lackawanna and State of Pennsylvania, have invented certain new and useful Improvements in Water-Heaters for Stoves, Ranges, &c.; and I do hereby declare the following to be a full, clear, and exact description of the same, reference being had to the accompanying drawings, forming 10 a part of this specification, and to the figures and letters of reference marked thereon.

My invention has for its object to provide for use in connection with stoves, ranges, &c., a water-heater which is capable of being applied or detached without putting out or at 15 all disturbing the fire in the fire-pot or fire-chamber.

The nature of my invention will be best apprehended from the following description, 20 taken in connection with the accompanying drawings, and the particular features of novelty will be pointed out in the clauses of claims at the end of the said description.

The drawings referred to show in Figure 1 25 a sectional view of the fire-chamber of a range with my improved water-heater applied thereto. Fig. 3 shows in perspective the inner side or face of the open or slotted wall of the fire-chamber. Fig. 2 shows the rear side of said 30 fire-chamber wall with the heating-pipe in position, the outer plate or cap being removed; and Fig. 4 is an end view of the stove, showing the outer plate or cap and the damper for covering the air-inlet thereof.

35 Similar letters of reference in the several figures indicate the same parts.

The letter A. indicates the wall of the fire-chamber through which the heater is applied. This wall is preferably formed of a single casting, and is formed with a series of partitions or fingers, a, supported at one end only, as shown, and so arranged as to leave a sinuous interval or open space, b b b b, extending uninterruptedly from top to bottom of the wall, 45 as clearly shown in Fig. 3.

Each of the fingers or partitions a is constructed of wedge-shape form in cross-section, being widest at the inner side next the fire and narrowest at the back. The wide front 50 face of each of the fingers or partitions is also preferably beveled backward from bottom to top, as shown at c d. The wall thus con-

structed is secured appropriately at one side of the fire-chamber, and constitutes the permanent wall thereof.

The water-heater proper consists, preferably, of a sinuously-bent pipe, D, adapted to fit into the correspondingly-shaped interval or space b b b b in the wall A without entirely filling said space, though nearly so, and having its lower and upper ends formed so as to be coupled to an induction-pipe, E, and an eduction-pipe, F, respectively. The fingers or partitions a project rearwardly, and when the heater-pipe is placed in position it rests 65 within the fingers, as shown in Fig. 1. A back plate or cap, G, covers completely the projecting fingers or partitions as well as the heater-pipe, upper and lower openings, g g', being provided for the outlet and inlet ends of 70 the heater-pipe, as shown. This outer plate or cap is secured in any suitable manner, and can be applied and removed at pleasure. It is preferably lined with a lining composed of 75 asbestos, i, for the purpose of preventing any escape of heat by radiation.

When the heater-pipe is placed in position, its inner surface comes in direct contact with the fire in the fire-chamber, and the wedge 80 shape of the fingers or partitions enables the circulation of heat entirely around its rear, the amount of heating-surface exposed being sufficient to cause a very rapid heating of the water circulating through the pipe. The 85 front face of the fingers or partitions need not necessarily be backwardly beveled, as shown; but I prefer that construction, for the reason that it assists largely in increasing the amount of pipe-surface exposed to the direct heat of 90 the fire.

When for any reason it is desired to remove the heating-pipe, the result can be easily and quickly accomplished by first disconnecting the induction and eduction pipes, then taking 95 off the outer plate or cap, and then finally removing bodily the heater-pipe. The removal of the heater-pipe in no way affects the contents of the fire-chamber, for whether or not the heater-pipe is in position the fingers or partitions a of the wall constitute the effective lateral support to the fuel in the fire-chamber.

In stoves and ranges as ordinarily constructed the water-heater or water-back is a fixture

and incapable of removal or of replacement without withdrawing the fire from the fire-box; but in my invention, as has been seen, the application or removal of the water-heater can 5 be effected at any time without trouble or inconvenience, or without disturbing the fire at all. This capability of ready removal is important, as it enables the water-heater to be withdrawn when from any reason the water- 10 supply fails and it is desired to prevent the empty water-heater from being subjected to the action of the fire.

It is obvious that the water-heater pipe may be constructed in different shapes and applied 15 to differently-formed walls, and I desire to be understood as covering all such obvious modifications, the essential feature of my invention consisting in applying to an open - sided or slotted fire-wall a heater which shall fill or 20 nearly fill the openings or slots in the wall, and be capable of application and removal at pleasure.

Provision is made for cooling somewhat the water-heating pipe, when desirable, without re- 25 moving said pipe from the stove or range, by the employment of a damper, *r*, arranged on the end or side or top of the outer plate or cap *G*, and adapted to cover or uncover at pleasure a series of openings in said plate or cap. 30 When the damper is moved so as to uncover the openings, cold air is admitted within the cap and the temperature of the water-heating pipe is thereby reduced. To exclude the cold external air the damper is moved in the op- 35 posite direction.

Having thus described my invention, what I claim as new, and desire to secure by Letters Patent, is—

1. The fire-chamber of a stove or range hav- 40 ing a slotted wall adapted to normally support the fire, and a water-heater adapted to be exposed to the fire through the slots or openings in the said wall, substantially as described.

2. The combination, with a fire-chamber 45 having a slotted wall, of a water-heater adapted, when inserted, to be exposed to the fire through the slots in the wall, and to be applied and removed at pleasure without disturbing the contents of the fire-chamber.

3. The combination, with the fire-chamber 50 having a slotted wall, of a water-heater exposed to the fire through the slots in the wall, and a back plate or cap inclosing the water-heater, so as to effect a circulation of heat behind and around the heater, substantially as 55 described.

4. In the herein-described water-heater, the combination of the wall having the fingers or partitions with the space between them, and the heater-pipe adapted to fit the space be- 60 tween the fingers, substantially as described.

5. The combination of the wall having the fingers or partitions of wedge-shaped cross- section, with the water-heater pipe.

6. The combination, with the wall having the 65 fingers or partitions of wedge-shape cross-sec- tion, of the water-heater pipe adapted to fit between the fingers, and the back plate or cap for inclosing the pipe and fingers, substan- tially as described. 70

7. The combination of the wall having the fingers or partitions made beveling on their faces next the fire, with the water-heater pipe, substantially as described.

8. The combination, with the wall having 75 the fingers or partitions of wedge shape in cross-section, and having the inclined front faces, of the water-heater pipe arranged in the space between the fingers, substantially as de- 80 scribed.

9. The combination of the wall having the fingers or partitions of wedge shape in cross- section provided with the inclined faces, with the water-pipe arranged in the space between the fingers and with the back plate or cap, the 85 whole constructed and arranged substantially as described.

10. The combination, with the fire-chamber having the slotted wall, of a water - heater adapted, when inserted, to be exposed to the fire 90 through the slots in the wall, and a back plate or cap inclosing the water-heater, and having openings closed by a damper, substantially as described. 80
